UNITED STATES PATENT OFFICE.

LUTHER C. BALDWIN, OF MANCHESTER, NEW HAMPSHIRE.

LOOM-REED.

SPECIFICATION forming part of Letters Patent No. 664,827, dated January 1, 1901.

Application filed January 6, 1898. Serial No. 665,745. (No model.)

To all whom it may concern:

Be it known that I, LUTHER C. BALDWIN, of Manchester, State of New Hampshire, have invented certain Improvements in Loom-Reeds, 5 of which the following, read in connection with the accompanying drawings, is a specification.

This invention relates to loom-reeds; and it consists in matter of construction pertaining to means for holding the heading-bar in place and strengthening the union thereof to the reed-ribs, all as hereinafter more fully described.

In the accompanying sheet of drawings, 15 Figure 1 is a side view, partly in section, showing part of a loom-reed constructed in accordance with and illustrating this invention. Fig. 2 shows the holding-staple and cap detached.

20 The reed-ribs 2 may be understood as of the usual construction, having the wire dents 4 interposed and held therebetween in the manner commonly employed and well known in such cases. Also it may be observed that 25 the heading-bar 6 is placed, as usual, adjacent to the wire dents for holding same in place and has a connection with the reed-ribs for giving brace and strength to the whole device.

In carrying out this invention the heading- 30 bar 6 is cross-grooved to provide therein a slot or recess 8, while the cap 9 is similarly provided with a groove 7 and is fitted over the heading-bar 6 with its open end on the reed-rib end, its slotted portion admitting the 35 neck or reduced part of the heading-bar 6 and its body part in the recess 8. The outer end of the cap will be substantially flush with the outer edge of the heading-bar, and through suitable openings in the end face of 40 the cap are put the shafts 5 or insertible parts of a staple or holding connection, whereby the cap is secured firmly to the end of the reed-ribs, preferably, as shown in the present

instance, by embedding the shaft 5 in a body 10 of pitch and rosin or other suitable cement 45 placed in the hollow chamber of the reed-rib and allowed to harden about the shafts 5 for securing the same in place, the shafts being turned at the ends for engagement with the cement to better hold against withdrawal. 50

Instead of the cement being employed a pointed staple may be used and driven into the end of the reed-rib; but I prefer to use the cement, as it gives a firmer hold, besides permitting of being heated to allow withdrawal of the staple at times for purposes of repairing the reed, and, too, it adds solidity and strength to the whole connection for resisting strain and consequently displacement, while arrangement of the caps in grooves of 60 the heading-bar for engagement therewith prevents the ribs of the reed from drawing apart.

I claim—

1. In a reed device, in combination, the reed-rib, the heading-bar, 6, the cap, 9, oversetting the bar and rib end and the holding connection engaged by its outer end to the cap, 9, and a body of cement in the chamber of the reed-rib having engagement with the shaft of 70 the holding device, all substantially as described.

2. In a reed device, in combination, the reed-rib, the heading-bar, 6, having recess, 8, the slotted cap, 9, oversetting the bar and rib end, 75 with its body part in the recess, 8, of the bar, and a holding connection engaged with the cap and reed-rib for holding the cap in place, substantially as described.

Signed at Manchester, New Hampshire, this 80 22d day of November, A. D. 1897.

LUTHER C. BALDWIN.
